UNITED STATES PATENT OFFICE.

BERNARD T. STEBER, OF MONTREAL, CANADA, ASSIGNOR TO THE DOMINION TUBULAR LAMP COMPANY, OF SYRACUSE, NEW YORK.

DESIGN FOR A TUBULAR LANTERN.

SPECIFICATION forming part of Design No. 21,254, dated December 22, 1891.

Application filed August 21, 1891. Serial No. 403,335. Term of patent 14 years.

To all whom it may concern:

Be it known that I, BERNARD T. STEBER, a citizen of the United States, residing at Montreal, in the Province of Quebec, Dominion of Canada, have invented and produced a new and original Design for Tubular Lanterns, of which the following is a specification, reference being had to the accompanying drawings, forming part thereof.

Figure 1 is a perspective view of a tubular lantern, showing my design. Fig. 2 is a perspective view of the upper portion of one of the tubes.

The leading feature of my design consists of a rib, which is arranged lengthwise upon the outer side of each tube and has its surface transversely corrugated.

A represents the base of a tubular lantern, B B the side tubes, C the bell, and D the globe.

E represents the rib, which is arranged ²⁰ lengthwise upon the outer side of each tube and has its outer surface transversely corrugated.

What I claim is—

The design for a tubular lantern, as herein ²⁵ shown and described.

Witness my hand this 11th day of August, 1891.

BERNARD T. STEBER.
